(21) Appl. No.: **29/318,542**

(57) **CLAIM**

(22) Filed: **May 22, 2008**

The ornamental design for a solid state lighting spot, as shown.

(30) **Foreign Application Priority Data**

Nov. 28, 2007 (EM) 000833512

DESCRIPTION

(51) **LOC (9) Cl.** **26-04**

FIG. 1 is a perspective view showing my design;

(52) **U.S. Cl.** **D26/2**

FIG. 2 is a front elevational view thereof;

(58) **Field of Classification Search** D26/1-4;
313/313, 315, 317, 318, 493; 315/52, 53,
315/56, 57, 58

FIG. 3 is a rear elevational view thereof;

See application file for complete search history.

FIG. 4 is a right side elevational view thereof;

(56) **References Cited**

FIG. 5 is a left side elevational view thereof;

U.S. PATENT DOCUMENTS

FIG. 6 is a top plan view thereof; and,
